CLAIM

The ornamental design for a speaker device with lights, as shown and described.

DESCRIPTION

FIG. 1 is a top plan view of a first state of a speaker device with lights, where a first indicator light is lit, showing our new design;

FIG. 2 is a top plan view of a second state, where a second indicator light is lit;

FIG. 3 is a top plan view of a third state, where a third indicator light is lit;

FIG. 4 is a top plan view of a fourth state, where a fourth indicator light is lit;

FIG. 5 is a top plan view of a fifth state; and,

FIG. 6 is a top perspective view of the first state shown in FIG. 1, where the first indicator light is lit.

The subject matter in this patent includes illuminated indicator lights of a speaker device with lights. The evenly-spaced broken radiating lines in FIGS. 1-4 and 6 are used to indicate an illuminated state of a corresponding circular indicator light on the speaker device with lights, the evenly-spaced broken radiating lines forming no part of the claimed design. The appearance of the transitional illuminated state sequentially transitions between the illuminated states shown in FIGS. 1-5. The process or period in which one illuminated state transitions to another illuminated state forms no part of the claimed design.

(Continued)

The dot-dash broken lines in the figures are boundary lines that define the bounds of the claimed design at a top portion of the speaker device with lights and form no part of the claimed design. The portions of the speaker device shown in evenly-spaced broken lines are for the purpose of illustrating environment only and form no part of the claimed design.
